UNITED STATES PATENT OFFICE.

WILLIAM E. HASKELL, OF BRATTLEBORO, VERMONT, ASSIGNOR TO ESTEY ORGAN COMPANY, OF BRATTLEBORO, VERMONT, A CORPORATION OF VERMONT.

ORGAN-PIPE.

965,898.

Specification of Letters Patent. Patented Aug. 2, 1910.

Application filed March 9, 1909. Serial No. 482,211.

To all whom it may concern:

Be it known that I, WILLIAM E. HASKELL, of Brattleboro, in the county of Windham and State of Vermont, have invented certain new and useful Improvements in Organ-Pipes, of which the following is a specification.

The present invention is based upon the discovery that certain tonal effects can be produced in labial organ pipes by providing them with qualifying complementary chambers which effects have heretofore only been secured by the employment of reeds.

For the purpose of explaining the invention, there will be described a labial organ pipe embodying the principles thereof which produces a clarinet tone. Such pipe is illustrated in the accompanying drawings where-in—

20 Figure 1 is a front view of the pipe. Fig. 2 is a longitudinal vertical section. Fig. 3 is a detailed front view on an enlarged scale illustrating the means for altering the fundamental pitch of the pipe for tuning purposes. Fig. 4 is a cross section.

Certain of the features of the illustrated pipe are the same as those set forth in United States Letters Patent No. 871,272, November 19, 1907, these similar parts being 30 those from the bottom of the pipe up to the place of its maximum diameter indicated at the point α . The body A of the pipe tapers and diverges gradually from the mouth C at its lower end up to this point α . The pipe 35 is shown with a foot B having a toe a and port b . Below the mouth is a cup E and opposite the mouth is a draft bridge F. In these respects the pipe is like that of said patent.

40 The improvement resides in the qualifying complementary chamber G and its relation to the main chamber of the pipe and in the tuning appliances.

The body A of the pipe terminates, so far 45 as its fundamental pitch is concerned, at the vertically elongated lateral opening d . The portion of the pipe from this opening down to the bottom constitutes the main chamber of the pipe. The pipe is extended above this 50 opening d to constitute the qualifying complementary chamber G. This surmounting and communicating complementary chamber may be in one piece with the main chamber of the pipe, but for convenience of 55 manufacture the two chambers are made in

two pieces united in any usual way employed in connection with metallic organ pipes, so as to constitute a substantially integral pipe. The entire pipe is made of the ordinary metallic compositions used in the manufacture of organ pipes. Both chambers are circular in cross section except where the body is flattened at the mouth. The complementary chamber is open at its top as shown at e , in Fig. 2. The complementary chamber G tapers from bottom to top, substantially as illustrated. As shown, there is a double convergence, the convergence being gradual or slight for about two-thirds of the distance above the top of the lateral opening d , and being greater or more abrupt for the remainder of the height. The complementary chamber can thus be regarded as having a gradual converging or tapering body and a conical open top.

The two chambers require independent tuning. The complementary chamber is tuned in a customary manner by means of a tuning slit f , and a tuning roll g . The main chamber is tuned by means of a split 80 sliding tuning sleeve H which frictionally embraces the part of the pipe where the two chambers join. This tuning sleeve has an upwardly extending rod i , for moving it and it is provided with a circular lateral 85 opening h , which is opposite the elongated slot d . The vertical elongation of the slot d , affords opportunity for an adequate range of adjustment.

The fundamental pitch of the pipe is determined by the opening h , in the tuning sleeve; while the pitch of the complementary chamber itself is determined by the effective distance between the opening h , and the top of the tuning roll g .

The effective acoustic height of the complementary chamber is one-half of that of the speaking or acoustic length of the main chamber. Mechanically, the height of the complementary chamber is more than one-half the height of the main chamber, and substantially in the proportion shown in the drawings. This difference between the relative acoustic and mechanical lengths is due to the flattening effect of the tapering 105 shape of the complementary chamber.

In the case of the pipe producing the clarinet tone, certain characteristics are important. The diameter of the opening h , at the union or junction of the two cham-

- bers, should be the same as the width of the mouth C and, as shown, it is substantially two-thirds the diameter of the pipe at the point where it is located. The tone 5 of the clarinet is composed of a fundamental vibration qualified mainly by the unevenly numbered harmonics, the most prominent of which is the fifth above its octave.
- 10 With the present improved pipe provided with the opening *h*, of the size shown, there is a combination both of the evenly and unevenly numbered harmonics; and the unevenly numbered harmonics which are characteristic 15 of the clarinet are due to the qualifying complementary chamber.
- I claim:—
1. A metallic organ pipe having a main chamber surmounted by and communicating 20 with an open top qualifying complementary chamber, the pipe having a lateral circular opening at the junction of said chambers, of a diameter substantially equal to the width of the mouth of the pipe, the 25 complementary chamber tapering upwardly and converging first gradually and then more abruptly, and the effective acoustic height of the complementary chamber being one-half of that of the speaking length 30 of the main chamber.
2. An organ pipe having a main chamber surmounted by and communicating with an open top qualifying complementary chamber, the pipe having a lateral opening 35 of a width substantially equal to the width of the mouth of the pipe, the complementary chamber tapering upwardly and converging first gradually and then more abruptly, and the effective acoustic height 40 of the complementary chamber being one-half of that of the speaking length of the main chamber.
3. An organ pipe having a main chamber surmounted by and communicating with an 45 open-top qualifying complementary chamber, the pipe having a lateral opening at the junction of said chambers, the complementary chamber tapering upwardly and converging first gradually and then more abruptly, and the effective acoustic height 50 of the complementary chamber being one-half of that of the speaking length of the main chamber.
4. An organ pipe having a main chamber 55 surmounted by and communicating with an open top qualifying complementary chamber, the pipe having a lateral opening of a width substantially equal to the width of the mouth of the pipe, and the effective 60 acoustic height of the complementary chamber being one-half of that of the speaking length of the main chamber.
5. An organ pipe having a main chamber surmounted by and communicating with a qualifying tapering complementary chamber, the pipe having an ever open lateral opening determining the speaking length of the main chamber, and the effective acoustic height of the complementary chamber being one-half of that of the speaking length of the body of the pipe. 65
6. An organ pipe having a main chamber and a surmounting qualifying complementary chamber constituting an upward extension to the pipe, there being a lateral opening at the union between said chambers, said opening determining the fundamental pitch of the pipe, and separate means for tuning the said two chambers respectively. 70
7. An organ pipe having a main chamber and a surmounting qualifying complementary chamber constituting an upward extension to the pipe, there being a lateral opening at the union between said chambers, said opening determining the fundamental pitch of the pipe, and separate means for independently tuning both the body of the pipe and the qualifying complementary chamber. 80
8. An organ pipe having a main chamber and a qualifying complementary chamber, there being a lateral opening at the union between said chambers, said opening determining the fundamental pitch of the pipe, and separate means for tuning both of said chambers respectively. 85
9. An organ pipe having a main chamber and a qualifying complementary chamber and separate means for independently tuning both chambers. 90
10. An organ pipe having a main chamber with a mouth at its lower end, a communicating qualifying tapering complementary chamber at the top, and an ever open opening where said chambers join, said opening determining the speaking length of the main chamber, and the complementary chamber having also an opening at its end. 105
11. A labial organ pipe having a main chamber with a mouth at its side at its lower end, a lateral opening above the mouth, and a qualifying complementary chamber communicating with the main chamber at said lateral opening, said complementary chamber converging first gradually and then more abruptly. 110
- In witness whereof, I have hereunto signed my name in the presence of two subscribing witnesses.
- WILLIAM E. HASKELL.
